Inventor:

Frederick D. Martin,
By Joshua P. Ross
Attorney.

UNITED STATES PATENT OFFICE.

FREDERICK DOAM MARTIN, OF KANSAS CITY, MISSOURI.

GARMENT-FASTENER.

1,368,818.

Specification of Letters Patent. Patented Feb. 15, 1921.

Application filed February 16, 1920. Serial No. 359,002.

To all whom it may concern:

Be it known that I, FREDERICK DOAM MARTIN, a citizen of the United States, and a resident of the city of Kansas City, county 5 of Jackson, and State of Missouri, have invented certain new and useful Improvements in Garment-Fasteners, of which the following is a specification.

My invention relates to new and useful 10 improvements in garment fasteners, and has for its object the provision of a garment fastener which is simple in structure, economic of manufacture and highly efficient in use. Another object is the provision of 15 a method of fastening in fixed relation the adjacent ends of fabric.

Other objects will appear hereinafter.

The invention consists in the combinations and arrangements of parts hereinafter described and claimed.

The invention will be best understood by reference to the accompanying drawings forming a part of this specification, and in which,

25 Figure 1, is a top plan view of the gromet used in the invention,

Fig. 2, a central vertical sectional view of the gromet applied to a fabric, and

Fig. 3, a perspective view of the invention.

My invention is designed primarily for use on butchers' and bakers' aprons and the like, and is intended to afford a simple and readily operated means of securing the ends

35 of the apron in fixed relation while being worn, and to afford a rapid and easy means of loosening the same. To this end I provide a gromet which is secured to the fabric 7 in the usual manner, in which gromets

40 are secured in fabric members. The gromet comprises an enlarged portion 8, connected by a neck 9 with a reduced eye 10. This

45 gromet, constructed as described, is secured in the fabric at the places where adjacent edges approach each other. A string or

50 cord 11, or other suitable member, is provided, which has a knot 12 formed at its opposite ends. The knot is first inserted through the enlarged portion 8 and then the

55 string is drawn along the neck 9 until the same engages in the eye 10. The knot is of such a size as to prevent its passage through the eye 10, and the garments are thus held in fixed relation to each other. In

use, one end of the string may be permanently fastened to the apron or garment

with which used, and the free end provided with the knot, in which case the gromets 8 will be fastened to the garment at only one side.

It has been learned from experience that the aprons which are now used, in which strings are permanently fastened to the adjacent meeting edges of the garment, are frequently removed by the wearer without 60 unfastening the strings. This is especially the case where the strings have become knotted. When these aprons in which the strings have become knotted are collected for laundrying, a great deal of work is necessary 65 and a great deal of time consumed in untying the knotted strings before the aprons can be washed. By the use of my invention, this time which is lost in unfastening the knotted strings is saved, and the actual cost of 70 laundrying the garments thereby greatly diminished.

While I have illustrated and described the preferred form of construction for carrying my invention into effect, this is capable of 75 variation and modification without departing from the spirit of the invention. I, therefore, do not wish to be limited to the precise details of construction set forth, but desire to avail myself of such variations and 80 modifications as come within the scope of the appended claims.

Having described my invention, what I claim as new and desire to secure by Letters Patent is:—

1. Garment fastening means comprising a 85 knotted member and a gromet adapted to be fastened to a garment, said gromet having an enlarged and a restricted portion, said garment being retained in position by passing said knot through the enlarged portion and drawing said member into the restricted portion, substantially as described.

2. Apron fastening means comprising a 90 cord and a gromet adapted to be secured to the meeting edges of said apron, said cord having a knot and said gromet having an enlarged portion and a restricted portion, said edges being held in fixed relation by passing said knot through the enlarged portion and drawing it over to bear against the restricted portion, substantially as described.

3. In combination with a garment having meeting edges, a gromet adapted to be secured in said garment adjacent one of said 105 edges, said gromet having an enlarged portion and a reduced portion connected there-

with by means of a restricted neck; and a knotted cord adapted to be fixed to the other edge of said garment, the knot passing through the enlarged portion and seating 5 against said reduced portion to retain said edges in fixed relation, substantially as described.

4. In combination with an apron having meeting edges, a gromet adapted to be secured in said apron adjacent one of said edges, said gromet having an enlarged portion and a reduced portion connected therewith by means of a restricted neck; and a

knotted cord attachable to the other edge of said apron, the knot being adapted to 15 pass through the enlarged portion and seat against said reduced portion to retain said edges in fixed relation.

In testimony whereof I have signed my name to this specification in the presence 20 of two subscribing witnesses.

FREDERICK DOAM MARTIN.
